UNITED STATES PATENT OFFICE.

CHARLES D. LANNING, OF BOSTON, MASSACHUSETTS, ASSIGNOR TO ODIN B. ROBERTS,
TRUSTEE, OF BOSTON, MASSACHUSETTS.

TELEPHONE REPEATING INSTRUMENT.

1,250,192.

Specification of Letters Patent. Patented Dec. 18, 1917.

Continuation of applications Serial No. 44,049, filed January 21, 1901, and Serial No. 291,530, filed December 13, 1905. This application filed August 2, 1911. Serial No. 641,947.

To all whom it may concern:

Be it known that I, CHARLES D. LANNING, a citizen of the United States, and a resident of Boston, in the county of Suffolk and 5 Commonwealth of Massachusetts, have invented an Improvement in Telephone Repeating Instruments, of which the following description, in connection with the accompanying drawings, is a specification, 10 like characters on the drawings representing like parts.

My invention has reference to instruments for repeating and thereby relaying or reinforcing telephone voice currents; and particularly to the class of such instruments embodying an electro-magnetic receiving 15 element and a variable resistance transmitting element controlled by such receiving element, the receiving element being connected into the incoming line and a transmitting circuit operatively controlled by 20 said variable resistance device being connected to an outgoing line.

In the operation of such an instrument it 25 is obvious that there are a number of successive transformations of energy and my invention in general consists in simplifying the instrument and in so arranging it that each coöperating part may perform its desired function with efficiency, and in connecting and arranging the parts so that 30 there will be as little energy loss as possible in the various transformations necessarily taking place and so that reproduction of the 35 voice-current wave may be accomplished with the minimum distortion thereof; whereby the desired object may be efficiently attained; such object being the establishing of a new and stronger current in which the 40 wave form of the received current shall be reproduced as accurately as possible.

I have illustrated my invention in the annexed drawings which are made in the various figures on slightly different scales from 45 working apparatus of which the principal portions of the receiving and transmitting devices (i. e. the receiving magnet and the transmitting microphone) are parts of the usual commercial transmitter and receiver 50 respectively as used on commercial telephone lines; which will indicate in general the size and proportion of parts that I find it advantageous to employ.

In the drawings Figure 1 is a plan view of one embodiment of my invention and 55 Fig. 2 is an elevation partially in section of the apparatus shown in Fig. 1.

Fig. 3 is a plan view of another embodiment of my invention substantially similar to Fig. 1 except that some of the auxiliary 60 parts therein illustrated are omitted.

Fig. 4 is an elevation partly in section of the apparatus shown in Fig. 3.

Fig. 5 illustrates another and slightly different embodiment of my invention being 65 substantially similar to what is shown in Fig. 1 except that the position of some of the coöperative vibratory parts is relatively reversed.

Fig. 6 is an elevation partly in section of 70 the apparatus shown in Fig. 5.

Referring to the drawings in general it will be seen that they all embody a similar mechanism for correlating the receiving and transmitting elements of the repeater. The 75 receiving element in each case y is the usual permanent magnet with soft iron pole-pieces as employed in the commercial receiver, with its windings, y' , y'' , mounted on soft iron pole-pieces attached to the permanent 80 magnet as clearly shown in plan in Figs. 1 and 3.

The magnet winding is placed in series with the receiving circuit through v , 2, coils y' , y'' , 3 and v' . This form of magnet is 85 adopted for its simplicity and demonstrated efficiency. The windings are of the usual type with approximately 100 ohms resistance. The permanent magnet provides an initial field as usual, acting upon the related 90 armature whereby the magnet is responsive differentially, and thereby cumulatively, as usual to the opposite phases of the received alternating line current.

In place of the provision of this initial 95 field by the permanent magnet, there might be provided additional windings for the creation of this initial field by a separate battery-energized circuit of the magnet; such means having been many times disclosed in 100 the published art relating to telephone repeaters and providing in some instances a useful means for regulating the strength of this initial flux of the receiving magnet whereby its initial strain upon the armature attached to the operated microphone 105

may be regulated. In place thereof I provide in the various forms shown a means for regulating the gap between the magnet and related armature as will be described in detail in connection with the separate figures, but either of such means may be employed.

Operatively the magnet is fixedly mounted on a supporting block or pedestal *t*. In the field of the magnet is supported a block armature *p* by rigid and central attachment to the vibratory electrode of the microphone. The provision of the armature in non-diaphragmatic form, that is, confining its function entirely to that of a responsive magnetic member, secures the maximum efficiency in the armature as part of the magnetic circuit. Not being limited in dimensions by considerations of flexibility it may be made as thick as desired and built in any other established manner, such as being provided with laminations or otherwise. By means of the adjusting mechanism as shown the air gap between the armature and magnet may also be established at a minimum distance and thus, with a magnet of efficient design, an armature so constructed and proportioned as to be more efficient magnetically than when limited in thickness as in diaphragms, and an air gap limited to the smallest practicable distance, the energizing windings being also as near the ends of the pole-pieces as practicable, a magnetic circuit and a receiving magnetic device of great efficiency is secured.

In all the forms shown the said block armature is rigidly and centrally attached to the vibratory electrode of the microphone. This microphone is provided in the form of what is known as the "solid-back" microphone as employed for some time past in the commercial transmitter in the Bell service. This microphone is shown in general outline in Figs. 1, 2, 5 and 6, and in detail in Figs. 3 and 4. It comprises, as is well understood in the art, a chamber having in the rear portion a plate carbon electrode. The front electrode is formed as part of a composite diaphragm-electrode structure; this structure being clamped upon the walls of the chamber in such manner that the diaphragm-electrode structure is maintained, preferably through granular carbon held in said chamber between the front and back electrodes, in electrical connection with said back electrode. The diaphragm-electrode structure is formed so that when assembled it has an interior plate carbon electrode and an exterior clamping member, an annular diaphragm preferably of mica being clamped therebetween and said diaphragm being clamped upon the walls of the chamber as above described; all as well understood in the art and as disclosed in a prior United States patent to A. W. White.

In all the forms of apparatus illustrated

herein, said microphone is shown fixedly mounted on a pedestal or support, which is a preferable but not essential construction.

It will be seen, therefore, that the armature member is separated in all forms from the vibratory electrode and diaphragm elements and also that the single diaphragm of the solid-back electrode structure constitutes the only diaphragmatic member involved in the vibratory operation of the connected armature and vibratory electrode. In this way not only is the armature provided in a design calculated to secure the greatest efficiency thereof but the vibratory electrode of the microphone is preserved in form, assembled, so that its freedom of movement and accuracy in performing its vibratory function, coöperating with the varying strain of the magnet, is not impaired. Where the vibratory electrode is subject to the control of more than one diaphragmatic member great difficulty is found in maintaining the diaphragms in parallel alinement and concentrically arranged; and unless such condition is preserved manifestly each diaphragm tends to restrain the action of the other and thereby the action of the microphone is much impaired.

I have provided in the preferred form of instrument herein shown as in Figs. 1 and 5 an auxiliary tension member to coöperate in the regulation of vibratory action, non-diaphragmatic in form, so that this difficulty of adjustment and resulting impairment of microphone operation may be avoided and at the same time the single diaphragm maintained as nearly as possible in an initially flat condition which is obviously its condition of greatest delicacy as related to freedom of vibratory movement; which auxiliary element I will later describe.

It will be seen, therefore, that in all the forms of instruments illustrated in the drawings the efficient character of the simplified repeater instrument that I have invented resides essentially in the provision of a receiving electro-magnetic element having as a coöperative member thereof a block armature disassociated in function from the vibration-controlling element of the microphone or from the electrode element or elements of the microphone; in mounting this block armature by central and rigid attachment to the vibratory electrode; and in providing the microphone in form where its vibratory electrode is a composite diaphragm electrode structure, constituting the only diaphragm element operatively related to the performance by the connected armature and vibratory electrode of their vibratory functions. It will be obvious that this construction, by disassociating the repeating instrument entirely from instruments designed to respond

to or to produce audible sound, supplies a current-actuated and a current-reproducing instrument in a simple and efficient form.

Referring to the drawings in detail, in

- 6 Fig. 1 the receiving magnet y is mounted as shown upon a block pedestal t which latter is mounted upon an adjusting carriage, the block t engaging the worm u so that the magnet may be given an adjusting 10 movement with reference to its relation to the armature p . This worm is provided with a milled end nut u^3 and a lock nut u^4 ; the said worm u receiving a permanent and controlling end thrust from the interposed 15 coil spring at one end thereof, u^6 . In this form of instrument the parts are interconnected so that any increase of attraction upon the armature p will result in increase of pressure in the microphone; and for that 20 purpose the armature p is mounted, by means of the connecting yoke q , centrally upon the vibratory electrode structure i of the microphone; the said yoke being preferably made, as in the instrument shown, of aluminum so as to be as light as practicable. 25 There is also connected to the vibratory electrode to oppose the initial magnetic strain on the armature as communicated to said vibratory electrode, the elastic c which is 30 connected at its other end to the tension adjustment means as shown comprising the worm e mounted in a pedestal as shown and carrying at its end the bracket d' , supporting the hook d , the latter engaging the said 35 elastic as stated. Said worm e is mounted for rotative movement in said bracket d' and an auxiliary rod d^2 parallel to the said worm e engages said bracket d' rigidly so that adjustment of said worm e by turning 40 thereof will not disturb the alignment of the bracket d' and hook d with reference to the said elastic c and connected hook b on the vibratory electrode structure.

The function of this elastic tensioning device is to assist in preserving the diaphragm of the diaphragm-electrode structure initially in a flat condition, whereby the most sensitive condition thereof is secured. To perform this function the co-operative spring 50 or tensioning device must be aperiodic in character; that is, it must have the quality inherent in diaphragms of responding accurately to the varying periods of vibration taking place in tone production and reproduction, without any dominant rate of vibration inherent in its own structure. An elastic under rectilinear extension fulfills these requirements as well or better than a diaphragm, whereas any coiled spring obviously tends to introduce its own rate of vibration and thereby impair other desired action. Such an elastic, however, may have an inherent rate of vibration at right angles to its axis of extension and for that purpose 60 65 I provide the intermediate vibration-check-

ing member n^2 , supported in contact with the elastic c by means of the arm n mounted in the pedestal m and held in position by the lock screw n' .

I find the provision of this rectilinearly extensible auxiliary tensioning device, preferably in the form of an elastic as shown, is of considerable advantage. The reason for this is that the action of the microphone is well recognized to be that its variations of conductivity are the result of variations of area of contact which latter are the consequence of varying pressure which implies movement. If the entire energy communicated to the block armature could be availed of in the form of movement of, and pressure between the electrodes, ideal efficiency would be secured. But in order to control the movement of the vibratory electrode and connected armature some form of mechanical vibration-controlling device is necessary in the form of instruments shown; and therefore part of the energy delivered to the armature must be expended in overcoming the resistance or inertia of this mechanical vibration controlling device. Diaphragms constitute very sensitive springs but their range of excursion is very limited; and upon very slight movement either way from a flat condition their further additional movement in the same direction is substantially restrained. Where, therefore, the diaphragm through its connected armature is under the initial strain of the electro-magnet and the current phase received by the receiving magnet is such as to still further increase the initial strain, it is substantially inoperative in producing further movement of, or pressure between, the electrodes, the energy being taken up in diaphragm resistance. If very large diaphragms are used for the purpose of enlarging the range of excursion, variations or inaccuracies of vibratory movement creep in requiring the use of damping springs upon various parts of the diaphragm such as those commonly employed with transmitter diaphragms. The function of the auxiliary tensioning device in the form shown, therefore, is to supply a tension acting against the initial magnetic tension to keep the diaphragm of the microphone initially in a substantially flat condition. The auxiliary device being provided as shown, is in a form having a very large range of movement relatively to the energy spent thereon, and is the equivalent in sensitiveness of a very large diaphragm. The result is that the mechanical resistance or inertia of the associated microphone diaphragm and auxiliary tensioning device is less, under the varying operating conditions, than the resistance of the diaphragm alone when initially distorted as would otherwise be the case. By providing the auxiliary tension and vibration-controlling device in this

form shown all difficulties of adjustment between two diaphragmatic members or damping of large diaphragms is avoided and I believe this combination of agencies puts 5 the purely mechanical part of the telephone repeating instrument in much better form than those heretofore disclosed in the art.

In Figs. 5 and 6 I have illustrated substantially the same general arrangement of 10 parts as shown in Figs. 1 and 2; the relation of the transmitting microphone and receiving magnet being, however, reversed; that is, being so positioned and respectively connected that any increase of attractive action 15 by the receiving magnet y on the armature p operates to decrease the conductivity of the microphone. The instrument being substantially similar in all respects to that shown in Figs. 1 and 2 no other description 20 will be necessary.

In Figs. 3 and 4 I have shown a form of the instrument in which the auxiliary vibration controlling member is omitted. In this form the receiving magnet is mounted on a 25 fixed pediment t , it being otherwise constructed and its circuit connected as above described in connection with the other figures. The transmitting microphone is mounted in a holder or pediment r , which is 30 carried in a support r^7 , being mounted therein on a worm r^5 provided with an end milled nut r^4 , and lock nut r^3 whereby the worm, being fixedly held in the end members r^2 , r^2' , on said support r^7 , may be utilized to give 35 the microphone and connected armature p a movement parallel with the end faces of the receiving magnet. Said support r^7 is in turn mounted upon the worm u carried in the bracket u' and u'' , the worm u being 40 provided with an end milled nut u^3 and lock nut u^4 , whereby the whole microphone and connected armature structure may be given a movement longitudinal of the microphone axis. By these adjusting means the 45 microphone and connected armature may be readily brought into any desired position with relation to the cooperating receiving magnet and there supported and maintained. The microphone is connected as before in series with a local battery circuit 50 through the binding posts 4^a , 6^a , and the circuit connections to the induction coil s^2 as shown, the secondary of the induction coil being connected into the transmitting 55 circuit as desired to the circuits as shown and the binding posts 7^a , 8^a .

The circuit connections in the various instruments are indicated by similar marking in the various figures.

60 It will be seen that in the form illustrated in Figs. 3 and 4 the essential features of my arrangement are embodied, but preferably I employ the forms illustrated in the other figures and for the reasons above 65 stated.

While I have herein shown and described for purposes of illustration one specific form of the invention, it is to be understood that the same is not limited to the details of construction or relative arrangement of parts but that extensive deviations may be made from the disclosed details without departing from the spirit of the invention.

Claims:

1. A telephonic voice-current repeating instrument, comprising an initially magnetized receiving magnet and its circuit connections; a transmitting microphone and its circuit connections, embodying a stationary 70 rear electrode, an opposed electrode in the form of a single, peripherally-clamped, non-magnetic, diaphragmatic, composite electrode-diaphragm structure, electrically related to said stationary rear electrode, with 75 the central axis of vibratory movement of said diaphragm-electrode structure substantially coincident with the central line of pull of said magnet; and a rigid block armature in the field of said magnet, rigidly and centrally attached to said diaphragm structure; together with an auxiliary vibration-controlling member for the microphone, in the form of a rectilinearly extensible member, disposed along the central axis of vibration 80 of the microphone diaphragm, extended by means of an attachment to an abutment and to the associated armature and vibratory electrode, and opposing the magnetic pull on the armature; said auxiliary tension member, as related to the said diaphragm member, having relatively large elastic limits and having a low inherent rate of vibration.

2. A telephonic voice-current repeating 85 instrument, comprising an initially magnetized receiving magnet and its circuit connections; a transmitting microphone and its circuit connections, embodying a stationary rear electrode, an opposed electrode in the 90 form of a single, peripherally-clamped, non-magnetic, diaphragmatic, composite electrode-diaphragm structure, electrically related to said stationary rear electrode, with the central axis of vibratory movement of 95 said diaphragm-electrode structure substantially coincident with the central line of pull of said magnet; and a rigid block armature in the field of said magnet, rigidly and centrally attached to said diaphragm structure; together with an auxiliary vibration-controlling member for the microphone, in the 100 form of a rectilinearly extensible member, disposed along the central axis of vibration of the microphone diaphragm, extended by means of an attachment to an abutment and to the associated armature and vibratory electrode, and opposing the magnetic pull on the armature; said auxiliary tension member, as related to the said diaphragm member, having a low inherent rate of vibration.

having relatively large elastic limits and a low inherent rate of vibration; said auxiliary tension member being non-metallic.

3. A telephonic voice-current repeating instrument, comprising an initially magnetized receiving magnet and its circuit connections; a transmitting microphone and its circuit connections, embodying a stationary rear electrode, an opposed electrode in the form of a single, peripherally-clamped, non-magnetic, diaphragmatic, composite electrode-diaphragm structure, electrically related to said stationary rear electrode, with the central axis of vibratory movement of said diaphragm-electrode structure substantially coincident with the central line of pull of said magnet; and a rigid block armature in the field of said magnet, rigidly and centrally attached to said diaphragm structure; together with an auxiliary vibration-controlling member for the microphone, in the form of a rectilinearly extensible member, disposed along the central axis of vibration of the microphone diaphragm, extended by means of an attachment to an abutment and to the associated armature and vibratory electrode, and opposing the magnetic pull on the armature; said auxiliary tension member, as related to the said diaphragm member, having relatively large elastic limits and a low inherent rate of vibration; said auxiliary tension member being further in the form of a stretched rubber strip.

4. A telephonic voice-current repeating instrument, comprising an initially magnetized receiving magnet and its circuit con-

nctions; a transmitting microphone and its circuit connections, embodying a stationary rear electrode, an opposed electrode in the form of a single, peripherally-clamped 40 non-magnetic diaphragmatic, composite electrode-diaphragm structure, electrically related to said stationary rear electrode, with the central axis of vibratory movement of said diaphragm-electrode structure substantially coincident with the central line of 45 pull of said magnet; and a rigid block armature in the field of said magnet, rigidly and centrally attached to said diaphragm structure; together with an auxiliary vibration-controlling member for the microphone, in the form of a rectilinearly extensible member, disposed along the central axis of vibration of the microphone diaphragm, extended by means of an attachment to an 50 abutment and to the associated armature and vibratory electrode, and opposing the magnetic pull on the armature; said auxiliary tension member, as related to the said diaphragm member, having relatively large 55 elastic limits and a low inherent rate of vibration; said auxiliary tension member having means to damp the vibration across its axis of extension.

In testimony whereof, I have signed my 60 name to this specification, in the presence of two subscribing witnesses.
